UNITED STATES PATENT OFFICE.

CHARLES R. NELSON, OF CHICAGO, ILLINOIS.

TEMPORARY BINDER.

No. 920,985.

Specification of Letters Patent.

Patented May 11, 1909.

Application filed July 25, 1906. Serial No. 327,603.

To all whom it may concern:

Be it known that I, CHARLES R. NELSON, a citizen of the United States, residing at Chicago, in the county of Cook and State of Illinois, have invented certain new and useful Improvements in Temporary Binders, of which the following is a specification.

This invention relates to improvements in temporary binders, and refers more specifically to an improved temporary binder designed as a transfer binder, *i. e.* a binder in which the disposed of contents of current books may be filed away permanently.

Among the salient objects of the invention are to provide a binder which constitutes a complete book binding as distinguished from those which have heretofore been used for this purpose having open backs and at the same time to produce such a binder well within the limits of reasonable cost; to provide such a transfer binder having sectional impaling pins or posts yet so constructed that these pins or posts at no time protrude beyond the sides of the book so as to scratch or deface furniture; to provide a transfer binder which is variable as to capacity over a wide range; to provide an improved means of reliably and conveniently locking the side members in adjusted relation upon the posts; to provide a transfer binder which is approximately uniform in appearance with the more elaborate and expensive books used currently, such as ledgers, day books, etc., and in general to provide an improved binder of the character referred to.

To the above ends the invention consists in the matters hereinafter described and more particularly pointed out in the appended claims.

The invention will be understood from the following description, reference being had to the accompanying drawing, in which—

Figure 1 is a perspective view of a preferred embodiment of the invention; Fig. 2 is a view in front elevation of the binder frame with the side covers detached, as for example shown in Fig. 3; the leaves being, however, interposed between the frame members and parts of said frame shown in longitudinal section on a plane coincident with the axes of the impaling posts; Fig. 3 is a transverse sectional view taken on line

3—3 of Fig. 2, the leaves, however, being omitted; Fig. 4 is a longitudinal sectional view taken approximately on line 4—4 of Fig. 2 and looking in the direction of the arrows; the leaves being in this instance also omitted.

Referring to the drawing, 1 and 2, respectively, designate as a whole binder frame members which are desirably of cast metal, such as aluminum, 3 and 3' designate the side covers which are hinged to the frame members 1 and 2 in any suitable manner, and 4 a detachable back which may be used with the binder or not as preferred.

The frame members 1 and 2 are desirably made of U-form in cross section, as best seen in Fig. 3, so as to secure at once rigidity, substantial thickness in the direction of the thickness of the binder, and relative lightness. At the points where the binding posts are seated, integral bridge blocks 5 are cast within the U-frames, and so also in the frame member 2 at a point intermediate its length a bridge block 6 is provided which is divided or recessed, as indicated at 7, for a purpose hereinafter explained. Externally the frame members are provided on their front sides with integral ears or lugs 8 which form hinge knuckles through which the pintles of the side covers are extended. The end ones of these ears are in transverse register with the impaling posts 9 and are transversely apertured to receive the latter. In the member 1 the butt end sections of the posts are permanently seated, and to this end the apertures 10 are counterbored to receive the correspondingly shaped engaging ends of the posts which are riveted permanently in place. The apertures 9' of the member 2 are of uniform diameter throughout so that the posts may slide freely therethrough. Caps 11 are desirably provided to form finishing terminals for each post, and these caps are made of such diameter that they also will pass through the apertures 9'.

In order to lock the frame members in adjusted relation, a threaded actuating rod 100 is seated to extend longitudinally within the frame member 2; the two end bridge pieces 5 being suitably apertured to receive said actuating rod and the bridge member 6 being longitudinally grooved to admit the rod, as seen clearly in Fig. 4. A confining

collar or annular rib 13 upon the rod 12 fits within and engages the sides of the recess 7 hereinbefore referred to and confines the rod against endwise movement. The respective ends of the actuating rod are reversely screw threaded, and upon each threaded portion is mounted a traversing locking block, as 14 and 14'. Rectangular ways are formed through the bridge members 5 to accommodate these locking blocks, as indicated at 15, the front sides of these ways being arranged to intersect the proximate sides of the post apertures 9' so that the laterally outer ends of the locking blocks will impinge against 15 and bite into the sides of the posts and thus lock the frame members in adjusted relation. In order to actuate the rod 12 one end thereof is squared to receive a key, as indicated at 16, and the end margin of the frame member 20 provided with a registering keyhole 17.

Describing now the detachable back member 4, this member desirably consists of a rigid cardboard or sheet metal plate or strip of a width approximately equal to the binder 25 when expanded to the desired capacity, shaped slightly convex as to its exterior, considered transversely, and desirably provided with end flanges 4' which overlap the ends of the leaves. From the body of the 30 back at points in transverse register with the respective binding posts, tabs 18 are struck out and turned inwardly to extend in a plane parallel with the leaves and preferably about midwidth of the back member. 35 These tabs are of suitable length to reach to and engage the binding posts, and are provided with perforated and slotted apertures 19 so that they may be engaged with the posts by simply forcing them inwardly between the leaves. As seen clearly in Fig. 4 40 these tabs serve the purpose of holding the back in position. It being understood that the slotted portion of the tabs have spring clamping engagement with the posts after 45 they are forced over the latter. In order to conceal the openings 20 formed in the back member by striking out the tabs, said back members are desirably provided with a covering of leather, cloth or other suitable 50 binding material, as indicated at 21. It is to be understood that a variety of widths of these back members will be made or supplied so that when the binder has been filled a back corresponding in width to the thickness 55 of the book may be selected and adjusted to position, and thus become a permanent part of the file.

It will be seen from the foregoing description that I accomplish the several objects of 60 the invention hereinbefore stated and produce a binder which is not only capable of being manufactured at an extremely moderate cost but forms a complete and perfect book binding for its contents. It is to be

particularly noted that the depth of the 65 socket openings 9 through which the impaling posts extend is such that the position of the binding member may be adjusted outwardly or inwardly over a range of adjustment nearly equal to the length of a post 70 section without exposing the ends of the post beyond the ends of the sides of the binder frame. Accordingly it is never necessary to have the posts protrude so as to deface furniture or disfigure the binder; it being 75 understood that the capacity of the binder may be enlarged within any reasonable limits by simply adding post sections, in a manner well understood in this art.

I claim as my invention:

1. In combination with a loose leaf binder, a detachable back consisting of a plate adapted to fit against the back end of the binder and provided with flat tabs projecting inwardly from its inner side parallel with the 85 leaf plane of the binder and detachably engaged with the impaling devices.
2. In combination with a loose leaf binder, a detachable back consisting of a plate conforming approximately to the width and length of the back of the binder provided with a plurality of integral inturned tab extensions adapted to extend flatwise between the contained leaves of the binder and detachably engaged with the impaling posts of 95 the latter.
3. In combination with a loose leaf binder, a detachable back consisting of a plate conforming approximately to the width and length of the binder, integral tabs struck out 100 of the body of said back and extended inwardly between the contained leaves of the binder and engaged with the impaling posts thereof, and an outer covering overlying the back plate and concealing the openings 105 formed by striking out the said tabs.
4. In a binder, the combination with a side frame member, binding posts extending through said member, a locking rod journaled to extend longitudinally within said frame member and confined against endwise movement therein, locking blocks threaded upon said locking rod, ways formed in said frame member through which said locking blocks reciprocate and whereby they are 110 held against rotation, said ways being arranged to intersect the binding post apertures at one side thereof, said locking blocks being adapted to impinge directly against said binding posts and tending to force the 115 latter outwardly toward one side of said frame member.

5. A binder comprising a pair of side frame members, each of semi-tubular or shell form in cross section, bridge portions extending across the interior of said shells, binding posts extending through said bridge portions, a locking rod journaled to extend longitudi- 125

nally within one of said side members, and confined against endwise movement therein, traveling locking blocks threaded on said locking rod and adapted to reciprocate in 5 suitable ways formed in said bridge portions, said ways being arranged to intersect the binding post apertures at the inner sides thereof whereby said locking blocks impinge directly against said binding posts.

CHARLES R. NELSON.
